UNITED STATES PATENT OFFICE.

JAMES E. BURKE, OF BENNINGTON, VERMONT, ASSIGNOR OF ONE-HALF TO COOPER MANUFACTURING CO., OF BENNINGTON, VERMONT, A CORPORATION OF VERMONT.

UNION GARMENT.

1,152,484.

Specification of Letters Patent.

Patented Sept. 7, 1915.

Application filed January 24, 1912. Serial No. 673,133.

To all whom it may concern:

Be it known that I, JAMES E. BURKE, a citizen of the United States, residing at Bennington, in the county of Bennington 5 and State of Vermont, have invented new and useful Improvements in Union Garments, of which the following is a specification.

This invention relates particularly though 10 not exclusively to improvements in union garments sometimes called "combination" or "union suits," the object being to provide a garment of the class set forth which shall have an opening extending from the neck 15 down the front, under the crotch and up the back to a point near the waistline, but which is so constructed or formed that the edges of said opening may be temporarily closed or retained in overlapped relation to each 20 other throughout their entire length and thus prevent exposure of the person of the wearer of said garment.

With this object in view, my invention consists in certain features of novelty in the 25 construction and arrangement of parts by which said object and certain other objects, which will hereinafter appear, are attained all as fully set forth in the specification and particularly pointed out in the claim.

30 Referring to the drawings: Figure 1 is a front elevation of a garment embodying my invention, a portion of the front of said garment being broken away to more clearly show the construction thereof. Fig. 2 is a 35 rear elevation of the garment shown in Fig. 1 with a portion thereof broken away and showing the crotch in section. Fig. 3 is a detail front elevation of the garment illustrated in Figs. 1 and 2 showing the lower 40 part opened. Fig. 4 is a view similar to Fig. 3 illustrating a modified form of my invention.

Like numerals refer to like parts throughout the several views of the drawings.

45 In the drawings, 6 is the front and 7 the rear of the body of an under garment having leg portions 8 and 9; 10 and 11 constitute edges of an opening in said garment formed during the construction thereof and 50 extend from the neck down the front into the inner seams of the leg portions 8 and 9, thence upwardly at the back to a point 12, preferably near the waistline. A gusset or flap 13 is secured to the edge 11 from a point 55 14 at the back⁷ of said garment upwardly

along said edge to the point 12, thence downwardly along the edge 10 into said inner leg seams to a point 15, thence upwardly along said edge 10 and terminating at a point 16 thereon, said point 16 being preferably substantially above the crotch of said garment. A second flap or gusset 17 is secured along the edges of said openings from a point 18 on the edge 10 upwardly to the point 12 at the rear 7 of said garment, thence 60 downwardly along the edge 11 to the lowermost point 19 of said opening in the inner leg seam of the leg 9 and substantially opposite to the point 15 of the leg 8, thence upwardly at the front of said garment to a 65 point 20 which is preferably substantially the same distance above the crotch as the point 16 on the opposite edge of said opening.

When the garment is closed the flaps 75 13 and 17 are adapted to overlap each other for substantially their entire lengths and at the rear thereof are adapted to be detachably connected and retained in said overlapped relation by a button 21, other means for 80 detachably retaining said flaps in overlapped relation to each other adjacent to the crotch and front portions of said garment being hereinafter described.

A facing or button stay 22 is secured to 85 one of the edges preferably 10 from the neck thereof downwardly to the point 16 which is the juncture of said edge with the edge of the flap 13, thence along the edge of said flap to the point 23, which is preferably 90 slightly beyond and at the rear of the crotch of said garment. To the opposite edge 11 or along the margin thereof is secured a facing 24 which extends from the neck of said garment downwardly to the point 20 which 95 is the intersection of said edge with the flap 17, thence along to a point 25, said facing being preferably coextensive with said button stay and adapted to be secured to said button stay by detachable means, preferably 100 consisting of a series of buttons 26 and buttonholes 27 on said button stay and facing respectively, the lowermost button 28 of said series of buttons being located at the front and at one side of the crotch of said 105 garment which is formed by said flaps (see Figs. 1, 3 and 4). By the use of the button 28 and the buttonhole 28', it will be seen that said flaps 13 and 17 will be firmly retained in their overlapped relation and 110

thereby prevent gaping of said flaps, even though the same should become greatly stretched, and thus provide all the advantages attained by a garment having a permanently closed crotch, but in addition providing a garment which may be opened, if so desired, from said neck down the front to the points 14 and 18 at the rear of said garment.

13 Referring now to Fig. 4, 10' and 11' are the edges of a garment similar in construction to the garment shown in Fig. 3, and 13' and 17' are flaps identical in construction with the flaps 13 and 17 illustrated in Fig. 3. A button stay 29 extends from the neck of said garment downwardly along the edge 10' to and beyond the point 16' to a point 30 on said edge 10', while to the opposite edge along the margin thereof is a facing 31 extending downwardly along the edge 11' to the point 20' which is the juncture of said edge 11' with the edge of the flap 17', thence along the edge of said flap and terminating at the point 32, which is preferably beyond 25 and at the rear of the crotch of said garment formed by the flap 17. The series of buttons 33, 33 are preferably connected to said button stay 29 and engage a series of buttonholes 34, 34 in the facing 31, and

when said buttons engage said buttonholes 30 said crotch will be temporarily closed.

Having thus described my invention what I claim and desire by Letters Patent to secure is:

14 A union garment having an opening extending down the front to the rear and terminating at a point in the back near the waistline, overlapping flaps substantially coextensive in area secured at one of their edges to opposite sides of said opening from 40 said point in the back to points at the front substantially above the crotch, and means to detachably secure the front edge of one of said flaps to the margin of the body portion of said garment at the front thereof and to 45 which the other of said flaps is secured, at points at one side of the crotch of said garment along one inner leg seam thereof and at a substantial distance from the edge of said other flap.

15 In testimony whereof I have hereunto set my hand in presence of two subscribing witnesses.

JAMES E. BURKE.

Witnesses:

WILLIAM W. BURKE,
A. J. COOPER.
